UNITED STATES PATENT OFFICE.

CHARLES D. WILLIAMS, OF ELMORE, MINNESOTA.

ATTACHMENT FOR VEHICLE-TONGUES.

No. 894,867.

Specification of Letters Patent. Patented Aug. 4, 1908.

Application filed November 6, 1907. Serial No. 401,021.

To all whom it may concern:

Be it known that I, CHARLES D. WILLIAMS, a citizen of the United States, residing at Elmore, in the county of Faribault and State of Minnesota, have invented certain new and useful Improvements in Attachments for Tongues; and I do hereby declare the following to be a full, clear, and exact description of the invention, such as will enable others skilled in the art to which it appertains to make and use the same.

My invention relates to new and useful improvements in attachments for tongues and more particularly to that class adapted to be employed in connection with vehicles and my object is to provide means for securing a tubular metallic tongue between the hounds of a vehicle.

A further object is to provide means for adjusting the attachments on the tongue, whereby they may be made to fit between hounds of varying widths.

A further object is to provide means for bracing the parts of the adjusting device and a still further object is to provide means for securing double trees to the tongue.

Other objects and advantages will be hereinafter referred to and more particularly pointed out in the claims.

In the accompanying drawings which are made a part of this application, Figure 1 is a plan view of a portion of the tongue, showing the manner of securing the same between the hounds of a vehicle. Fig. 2 is a perspective view of a portion of the adjusting mechanism. Fig. 3 is a perspective view of another portion of the adjusting mechanism. Fig. 4 is a sectional view as seen on line 4—4, Fig. 1. Fig. 5 is a sectional view as seen on line 5—5, Fig. 1, and Fig. 6 is a sectional view as seen on line 6—6, Fig. 1.

Referring to the drawings in which similar reference numerals designate corresponding parts throughout the several views, 1 indicates a tongue, which is preferably tubular and 2 indicates the hounds of the vehicle.

In securing the tongue between the hounds, I provide a pair of straps 3, the ends of which are provided with inwardly extending projections 4 and 5, which are substantially at right angles to the longitudinal plane of the straps and each projection is provided with a forwardly extending ear 6 and 7, respectively.

The projections 4 are adapted to engage one arm 8 of angle plates 9, while the opposite arms 10 are secured to the tongue by means

of bolts 11 and 12, which pass through the tongue and the arms 10. The face of the arms 8, engaged by the projections, is provided with serrations 13, so that when the projections and arms are clamped together, they will be positively held against slipping.

The bolt 12 extending through the tongue is threaded at both ends and is of sufficient length to extend through openings in the ears 6, so that the straps 3 may be readily adjusted towards or from the tongue and to hold said straps in their adjusted positions, nuts 14 and 15 are placed on opposite sides of the ears 6, so that when the straps have been properly adjusted, the nuts are clamped against the opposite faces of the ears to hold the straps. A bolt 16 is anchored to the inner end of the tongue 1 and extends laterally from each side thereof, the ends of said bolt 75 being adapted to receive the ears 7 and said ears are locked in their adjusted positions by means of nuts 17 and 18, which are adapted to engage, respectively, the outer and inner faces of the ears 7 and it will be seen that when it is desired to adjust the straps inwardly or outwardly, the nuts 14 and 15 on the bolt 12 and the nuts 17 and 18 on the bolt 16, may be loosened from the ears and the straps moved to the desired position, when the nuts are again engaged with their respective ears and the straps locked in their adjusted position.

The straps 3 are securely braced by providing a pair of brace rods 19, the forward ends of which are secured to a collar 20, while the opposite ends thereof are threaded and extended through slots 21 in the projections 4 and through slots 22 in the arms 8, the threaded portions of said brace rods having nuts 23 and 24 thereon, which are adapted to be placed at opposite sides of the interposed projections and arms, so that said projections and arms may be securely clamped together and by clamping the collar 20 on the tongue, as best shown in Fig. 5, the brace rods may be adjusted longitudinally, as desired.

In view of the fact that the tongue is tubular, a platform 25 is secured to the tongue and supported a distance above the same by means of depending standards 26, which are formed to fit the periphery of the tongue and are secured thereto by means of bolts 27 and the double tree 28 is held in position on the platform by means of a bolt 29, the lower end of which extends through an opening in the platform and through the tongue. The up-

per end of the bolt 29 is engaged by one end of a hammer strap 30, the opposite end of the strap being pivotally secured to the tongue 1 by means of a bolt 31, which extends through 5 the tongue and is provided at its upper end with a hook terminal 32, the free end of the terminal engaging a socket 33 in the upper face of the tongue, thereby forming a staple through the end of the hammer strap. After 10 the straps have been properly adjusted, the tongue is introduced between the hounds and secured thereto by means of a rod 34.

32 It will thus be seen that I have provided a very cheap and economical means for adjusting 15 securing a tongue to the hounds of a vehicle and one wherein the securing devices will be positively held in their adjusted positions. It will further be seen that the parts of the securing devices will be greatly reinforced 20 by providing the brake rods.

What I claim is:

1. In a securing device of the class described, the combination with a tubular tongue and hounds to receive said tongue; of 25 straps at each side of said tongue, inwardly extended projections at each end of said straps, forwardly extending ears on said projections, bolts extending through said tongue and having their ends threaded, nuts on said 30 bolts, adapted to engage said ears and secure the straps in their adjusted positions, angle plates on said tongue, one arm of each of which is provided with serrations and adapted 35 to engage the forward projections on the straps, brace rods for said straps, means to

adjustably secure the rods to the tongue, the inner ends of said rods being threaded and adapted to extend through said forward projections and nuts on said threaded ends adapted to clamp the projections and angle 40 plates together.

2. In a securing device of the class described, the combination with a tubular tongue and hounds to receive said tongue; of straps on each side of said tongue, inwardly 45 extending projections at the ends of the straps, forwardly extending ears on said projections, a pair of bolts extending through said tongue and through said ears, nuts on said bolts adapted to engage the ears and 50 hold the straps in their adjusted positions, the forward projections having slots therein, angle plates secured to said tongue and adapted to engage the forward projections, the engaging faces of said angle plates having 55 serrations, brace rods adjustably secured to said tongue, the free ends of said rods being threaded and adapted to extend through said slots in the projections and through the angle plates, nuts on said rods, adapted to 60 clamp the projections and plates together and a platform on said tongue, adapted to support a double tree.

In testimony whereof I have signed my name to this specification in the presence of 65 two subscribing witnesses.

CHARLES D. WILLIAMS.
